UNITED STATES PATENT OFFICE

AMBROSE D. OLDS, OF WICHITA, KANSAS, ASSIGNOR TO THE COLEMAN LAMP & STOVE COMPANY, OF WICHITA, KANSAS

DESIGN FOR A PERCOLATOR

Application filed February 21, 1930. Serial No. 34,606. Term of patent 7 years.

To all whom it may concern:

Be it known that I, AMBROSE D. OLDS, a citizen of the United States of America, residing at Wichita, in the county of Sedgwick and State of Kansas, have invented a new, original, and ornamental Design for Percolators, of which the following is the specification, reference being had to the accompanying drawings, forming a part thereof.

The figure is a perspective view of a percolator showing my new design.

I claim:

The ornamental design for a percolator as shown.

In testimony whereof I affix my signature.

AMBROSE D. OLDS.
